Primary Examiner — Karen S Acker(57) **CLAIM**

The ornamental design for a fireplace ficarella, as shown and described.

DESCRIPTION

FIG. 1 is a front perspective view for a fireplace showing my new and original design;

FIG. 2 is a second perspective view thereof;

FIG. 3 is a front elevation view thereof;

FIG. 4 is a right side elevation view thereof; and,

FIG. 5 is a left side elevation view thereof.

The broken lines showing of environment are for illustrative purposes only and form no part of the claimed design.

The bottom, back and top sides of the fireplace form no part of the claimed design.

The broken lines and the spaces within the broken lines in the drawings represent unclaimed environmental subject matter.
